CLAIM

The ornamental design for a bag, as shown and described.

DESCRIPTION

FIG. 1 is a front elevation view of a bag showing my new design;

FIG. 2 is a back elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a perspective view thereof illustrating a use state of the bag;

FIG. 8 is a front elevation view thereof illustrating a folded state of the bag;

FIG. 9 is a back elevation view thereof illustrating the folded state of the bag;

FIG. 10 is a top plan view thereof illustrating the folded state of the bag;

FIG. 11 is a bottom plan view thereof illustrating the folded state of the bag;

FIG. 12 is a left side elevation view thereof illustrating the folded state of the bag;

FIG. 13 is a right side elevation view thereof illustrating the folded state of the bag;

FIG. 14 is a perspective view thereof illustrating the folded state of the bag; and,

FIG. 15 is a perspective view thereof illustrating the compactly folded state of the bag.
